(57) **CLAIM**

The ornamental design for a mandibular advancement appliance, as shown and described.

DESCRIPTION

FIG. 1 is a front perspective view of a mandibular advancement appliance;

FIG. 2 is a bottom perspective view of the mandibular advancement appliance shown in FIG. 1;

FIG. 3 is a rear view of the mandibular advancement appliance shown in FIG. 1;

FIG. 4 is front view of the mandibular advancement appliance shown in FIG. 1;

FIG. 5 is a left side view of the mandibular advancement appliance shown in FIG. 1;

FIG. 6 is a right view of the mandibular advancement appliance shown in FIG. 1;

FIG. 7 is a top view of the mandibular advancement appliance shown in FIG. 1;

FIG. 8 is a bottom view of the mandibular advancement appliance shown in FIG. 1;

FIG. 9 is a front exploded perspective view of the mandibular advancement appliance shown in FIG. 1; and,

FIG. 10 is a bottom exploded perspective view of the mandibular advancement appliance shown in FIG. 1.

The broken lines in the drawings depict portions of the mandibular advancement appliance that form no part of the claimed design.
